US00D956228S

(12) **United States Design Patent** (10) **Patent No.:** **US D956,228 S**
(45) **Date of Patent:** **** Jun. 28, 2022**

(54) **ERGONOMIC MENSTRUAL DEVICE WITH
ELONGATED REMOVAL STEM**

Primary Examiner — Wan Laymon

(71) Applicant: **Christine Beatrice Brown**, Carpinteria, CA (US)

(57)

CLAIM

(72) Inventor: **Christine Beatrice Brown**, Carpinteria, CA (US)

The ornamental design for an ergonomic menstrual device with elongated removal stem, as shown and described.

(73) Assignee: **Wevotopia LLC**, Carpinteria, CA (US)

DESCRIPTION

(**) Term: **15 Years**

(21) Appl. No.: **29/744,185**

(22) Filed: **Jul. 28, 2020**

FIG. 1 is a front three-dimensional view of an ergonomic menstrual device with elongated removal stem showing my new design;

(51) LOC (13) Cl. **24-02**

FIG. 2 is a top plan view thereof;

(52) U.S. Cl.

FIG. 3 is a top three-dimensional view thereof;

USPC **D24/141**

FIG. 4 is a perspective three-dimensional view showing the top and rear sides thereof;

(58) **Field of Classification Search**

FIG. 5 is a perspective three-dimensional view showing the bottom and right sides thereof;

USPC D24/141, 121, 124-125

FIG. 6 is a perspective three-dimensional view showing the bottom and left sides thereof;

CPC A61F 5/4553; A61F 5/455; A61F 6/06;

FIG. 7 is a perspective three-dimensional view showing the top, front, and left sides thereof;

A61F 6/08; A61F 6/12

FIG. 8 is a bottom three-dimensional view thereof;

See application file for complete search history.

FIG. 9 is a front three-dimensional view of a second embodiment of an ergonomic menstrual device with elongated removal stem;

(56) **References Cited**

FIG. 10 is a right side three-dimensional view thereof;

U.S. PATENT DOCUMENTS

FIG. 11 is a rear three-dimensional view thereof;

FIG. 12 is a perspective three-dimensional view showing the bottom and left sides thereof;

(Continued)

FIG. 13 is a bottom three-dimensional view thereof;

FIG. 14 is a top plan view thereof;

FIG. 15 is a top three-dimensional view thereof; and,

FIG. 16 is a perspective three-dimensional view showing the top, front, and left sides thereof.

The broken lines are included for the purpose of illustrating portions of an ergonomic menstrual device with elongated removal stem that form no part of the claimed design.
